RADIO-PHONOGRAPH OR SIMILAR ARTICLE

Ken Okabe and Nara Hircaki Yazawa, Yamatokoriyama, Japan, assignors to Matsushita Electric Industrial Co., Ltd., Osaka, Japan

Filed Apr. 6, 1971, Ser. No. 131,839

Term of patent 14 years

Int. Cl. D14—03

U.S. Cl. D56—4 B

FIG. 1

FIG. 2

FIG. 3

FIG. 1 is a left side, top and front perspective view of a radio-phonograph or similar article, showing our new design;

FIG. 2 is a left side, top and front perspective view, the transparent dust cover being removed and omitted for convenience of illustration; and

FIG. 3 is a right side, bottom and rear perspective view thereof, the transparent dust cover being removed and omitted for convenience of illustration.

Portions of the figures are diagonally lined to indicate transparency, and portions are shaded to indicate contrast in appearance.

The structure which would be visible through the transparent cover of FIG. 1 has been omitted for convenience in illustration.

We claim:

The ornamental design for a radio-phonograph or similar article, as shown and described.
